CLOSURE

Robert Nyden, Manhasset, N. Y., assignor to F. N. Burt Company, Inc., Buffalo, N. Y., a corporation of Delaware

Application May 9, 1942, Serial No. 442,299

1 Claim. (Cl. 215—43)

This invention relates to a new and improved closure of the "screw-cap" type.

It is an object of the invention to provide a cap of this character that may be economically and rapidly fabricated from materials readily subject to die cutting and die scoring. Due to current restrictions in the use of metal, it is a major object to provide such cap readily adapted to manufacture from paper, cardboard, chipboard, plastics and similar materials, and which will lend itself to ready fabrication in large volume.

Another object is that of providing a cap of this kind constructed in an improved manner whereby it is sufficiently durable and wear-resistant to withstand normal wear over a considerable period of time and which will not discolor or contaminate the container or contents with which it is utilized.

Another object is that of providing a closure of this kind with an improved sealing structure adapted for use with creams, paste, liquids and other substances that require a substantially air-tight seal between the container and the closure.

With these and other objects in mind, reference is had to the attached drawing, in which:

Fig. 1 is a plan view of the inner member of one embodiment of the improved closure in partially formed conditions;

Fig. 2 is a cross section taken through a container with a finished closure embodying the inner member of Fig. 1 in place thereon;

Fig. 3 is a perspective view of the outer member of the closure shown in Fig. 2;

Fig. 4 is a perspective view of the inner closure member shown in Fig. 1 in its completed condition and before assembly with the outer closure member shown in Fig. 3;

Fig. 5 is a container showing a threaded neck portion adapted to receive the improved closure;

Fig. 6 is a plan view similar to Fig. 1 showing a modified type of inner closure member; and

Fig. 7 is a cross section of a completed closure embodying the inner closure member shown in Fig. 6.

As shown in Figs. 1 to 5 of the drawing, the improved closure member comprises an outer cover or body portion 16 having a depending peripheral flange 17 shown as being integrally formed with the top of the outer body member and forming a cup-like unit. Although the depending flange 17 is shown as being formed integrally with the top of the outer cover member 55

and this is a preferred manner of forming it, it will be understood that the structure of this cup-like member may be varied.

Cooperating with this outer flanged or cup-like member 16 in the formation of a completed closure is an inner body 18 which may be slightly domed as shown in Fig. 2 both to conform substantially with the doming of the outer body 16 and to provide a tensioning means. As shown in Fig. 1, the inner body 18 may be die cut or stamped from a flat sheet of paper, fibreboard, cardboard or the like, and have embossed in it at the time of stamping operation, an annular depressed sealing ring 19. Tabs 20 extend outwardly from the periphery of the inner disk-like body 18 and have embossed in them segments of screw threads as at 21. Thereafter, the inner disk-like member 18 shown in Fig. 1 is placed in a forming machine and the tabs 20 are turned downwardly so that the member takes the form shown in Fig. 4. It is then inserted within the outer cup-like member 16 shown in Fig. 3 and the down-turned flanged portions 20 due to the resiliency, frictionally engage the inner surfaces 25 of the annular flange 17 of the member 16. The outer member with its integral depending flange 17 thus forms a support for the inner body or disk-like member 18 and said flange 17 serves as a back support to prevent undue displacement 30 of the peripherally arranged depending flanges 20 during application of the closure in closing relation on the container.

If desired, a suitable adhesive can be utilized to hold the inner member 18 in position within the outer member 16.

While I have indicated that a separate forming machine is used to turn the tabs downwardly, it is quite apparent that a single machine might be used for the complete operation. As indicated in Fig. 2, it will be noted that when the screw cap or closure is put in position on the container, the annular sealing ridge 19 engages the upper surface 25 of the open mouth of the container.

The container body 22 may be formed of any suitable material such as glass, porcelain, paper or plastics and may be of any desired configuration. The container is preferably provided with a shoulder 23 from which rises a neck or mouth portion 24. Raised on this neck or mouth portion are suitable screw threads, for example, as shown at 26. The embossed thread segments 21 in the closure tabs 20 follow the same pitch as the thread 26 of the container neck, so that

when the cap is screwed in position on the container, the threads co-act.

Turning now to Figs. 6 and 7, there is illustrated an inner disk-like closure body 27 having depending annular flange or tab portions 28 in which a thread 29 is embossed. It will be noted that in this embodiment the tab portions or flange sections 28 are adjacent to each other and close together at the line of attachment or merging with the member 27, whereas in the preceding embodiment they are considerably spaced. Either form is advantageous, but in this embodiment for use where a precision fit is desirable, the thread segments are closer to one another and therefore afford more gripping area on the threads of the container. In assembling the inner closure or disk-like member 27 as shown in Fig. 7 into the outer closure 31, a spacer ring 32 usually formed of a material similar to that of other parts of the closure i. e. paper, cardboard, plastics etc., is preferably inserted between the depending flanges or side walls of the inner member and the outer member. Among other advantages, this spacer furnishes a resilient cushion thereby providing a tight compressive seal as well as furnishing a compensating means for diameter variation or tolerance. In this embodiment as in that previously described the outer flange 30 of the outer cup-like member 31 forms a back support against which the cushioning and sealing ring 32 is compressed by outward movement of the flanges 28 during application of the closure to the container. Thus the sealing ring 32 due to its resilient compressibility and cushioning effect serves as a compensating means for slight diameter variations of the container neck and closure member. While a press fit engagement of the parts will hold them in assembled position, adhesive again may be utilized if desired.

As pointed out above, each of the different embodiments of the improved closure is well adapted for fabrication from non-metallic ma-

terials. As indicated, the preferred materials are paper, cardboard, fiberboard, any of the well known plastics, and the like.

Since certain changes may be made in the above construction and different embodiments of the invention could be made without departing from the scope thereof, it is intended that all matter contained in the above description or shown in the accompanying drawing shall be interpreted as illustrative and not in a limiting sense.

I claim:

A closure for containers including, in combination, a cup-like outer member having a peripheral depending outer flange, a disc-like inner member having integral therewith a series of peripherally arranged separate depending flange members positioned to receive parts of the container, screw thread segments on said depending flange members for engagement with the container, said depending flange members being received within said depending flange of said outer member and being free to swing outwardly toward said outer flange which serves as a back support for said depending flange members to limit outward swinging movement thereof, said depending flange members being resilient and resiliently urged to swing outwardly toward said outer flange into frictional retaining relation therewith for frictionally retaining the inner and outer members in assembled relation, and a sealing member of compressive cushioning material interposed between said depending outer flange and said depending inner flange members and cooperating therewith so as to be compressed against said outer flange by outward movements of said inner depending flange members caused by application of the closure to the container and to serve as a compensating cushion for slight diameter variations of the engaging parts of the closure and container.

ROBERT NYDEN.
